[57] **CLAIM**

The ornamental design for an ornamental graphic audio equalizer, as shown and described.

DESCRIPTION

FIG. 1 is a front, top and left perspective view of an ornamental graphic audio equalizer showing my new design;

FIG. 2 is a front elevational view thereof;

FIG. 3 is a left side elevational view thereof;

FIG. 4 is a right side elevational view thereof;

FIG. 5 is a bottom plan view thereof; and,

FIG. 6 is a rear elevational view thereof.

FIGS. 1 and 3-5 are shown broken away to indicate the indeterminant length of the ornamental graphic audio equalizer.
